UNITED STATES PATENT OFFICE.

ROBERT THOMPSON, OF JERSEY CITY, NEW JERSEY.

GAS-STOVE.

1,271,243.

Specification of Letters Patent.

Patented July 2, 1918.

Application filed October 19, 1916. Serial No. 126,566.

To all whom it may concern:

Be it known that I, ROBERT THOMPSON, a citizen of the United States, residing at Jersey City, in the county of Hudson and State of New Jersey, have invented certain new and useful Improvements in Gas-Stoves, of which the following is a specification.

My invention relates to a gas burner or stove. Primarily I aim to provide an article of this type constructed for detachable connection to a gas-jet or other source of gas supply. This article may optionally be used for any usual purpose, for instance, for cooking or for heating.

In attaining said main objects, the desiderata are to provide a novel, improved, simplified and efficient construction; one having a special form of means for attachment to a gas jet; one having an improved means to control the inlet of air for admixture with the gas; one having an effective form of joint between the gas tube and the rose or burner; one having a novel type of article-supporting means disposed above and supported from the burner, and one having the latter means preferably foldable.

With the above and additional objects appearing hereinafter, in view, the invention has been embodied in one preferred form as illustrated in accompanying drawings, wherein:

Figure 1 is a vertical sectional view showing my improved stove attached to a gas jet suggested in dotted lines;

Fig. 2 is a top or plan view of the improved stove;

Fig. 3 is a bottom view of the valve means, the latter being partly broken away;

Fig. 4 is a cross sectional view on the line 4-4 of Fig. 1, and

Fig. 5 is a fragmentary vertical sectional view illustrating the method of fastening the legs of the attaching tube-positioning frame in place.

Referring specifically to the drawings, my improved stove or burner device is adapted for connection with any suitable source of gas supply but preferably with a gas jet as suggested at 5 in Fig. 1 by the dotted lines. It will be noted that a shoul-

der is provided at 6 where the gas jet connects with its supply tube or pipe 7. I provide a substantially frusto-conical hollow gas tube at 8 which is adapted to be connected in any suitable manner to the jet 5. Preferably a tube or thimble 9 is disposed axially of the tube 8 and adapted to be inserted over the end of the gas jet 5 and surrounds the jet with its lower ends resting on the shoulder 6 as seen in Fig. 1. A suitable skeleton frame is disposed within the tube 8 having a ring 10 surrounding the tube 9 and resting on lugs 11 struck outwardly or radially from the tube 9. Depending downwardly and outwardly from the ring 10 are legs or tines 12, at their lower ends bent outwardly so as to overlap an outwardly extending flange 13 at the base of tube 8, as at portions 14. These portions 14 are disposed intermediate said flange 13 and clenched thereto through the clenching of the marginal edge of a plate 15 against the flange 13, as at 16. The tube 9 extends through the plate 15 and also through a plate 17 which is journaled on the tube and has a marginal flange at 18 bent around the portion 16. Portion 18, however, is not clenched against portion 16, since the plate 17 is to be turned relatively to the plate 15 axially. The plate 15 has one or more openings 19 therein adapted to coöperate with one or more openings 20 in the plate 17 upon turning of the plate 17 so that the extent of the openings may be controlled. Plates 15 and 17 can turn only to a limited extent in view of the provision of a lug 20' on the plate 17 and which extends into one of the openings of each plate and is adapted to abut the plate 15 at opposite ends of the slot or opening thereof into which the lug extends. Since these openings admit air into the tube 8, the supply or quantity of air admitted may be regulated according to the principle of the Bunsen burner. It may be mentioned that the lower extremity of the tube 9 is bent outwardly to form a flange at 21 to assist in maintaining the valve 17 in place, and also that the tube 9 is rigidly connected to the plate 15 as at 22.

The burner is substantially a rose, having a greater cross sectional area than the tube

8. Its hot plate or crown is shown at 23 as raised above the top of the body of the burner consisting of downwardly and inwardly converging walls 24 from which a base or bottom 25 extends inwardly. While the rose or burner may be connected to the tube 8 in any suitable manner, yet I preferably aim to provide such a means as will avoid the use of rivets or additional fastening means. As shown in Fig. 1 of the drawings, the tube 8 adjacent its top may be bent and shortened to provide the outwardly extending annular rib 26 on which the bottom wall 25 rests. The top of the tube 8 is bent outwardly at a flange 27 to overlap the bottom wall 25 and flange 26. Bottom 25 and flange 27 are clenched together to form an effective and leak-proof joint. The body 24 at its top has an outwardly extending flange 28 around which is clenched a flange 29 of the plate 23. The crown of plate 23 is connected with the flange 29 by an inclined portion which is cut away at suitable intervals to provide openings 30 through which the gas issues for ignition.

In use, the valve of the gas jet 5 is opened after the tube 8 has been properly disposed over the jet by the tube 9 extending over the 30 jet and around it, resting on the ledge or shoulders 6. The gas will issue from the jet, rising in the tube 8 and burner 24 and issuing from the openings or orifices 30 where it is ignited. I preferably desire a blue flame or 35 reducing flame at the burner and therefore the valve 17 is provided to coöperate with the valve or plate 15. The plate 15 is manually turned axially so as to control the extent of the openings 19 and 20, and thereby 40 control the quantity of air admitted for admixture with the gas. The stove may be used either for heating or cooking purposes.

Preferably I provide a supporting means for cooking utensils or other articles above the burner or hot plate 23. In this connection I may use a T-shaped supporting member 31 which is crossed at right angles by a T-shaped supporting member 32 and which extends into a slot 33 of member 31 so that the top of members 31 and 32 will be flush as seen in Fig. 1. Each member has a riser 34 from which a plurality of tangs 35 extend and which latter are secured as by rivets 36, or any other suitable means, to the plate 23. Each riser preferably has two arms and the arms of each riser extend in opposite directions. It will be seen that the members 31 and 32 in effect provide four arms which radiate from the longitudinal 55 median line of the stove.

Pivotedly connected at the outer extremities of the said arms, as by means of rivets 37, are combined guards and supporting members having arms 38 through which the rivets pass and arms 39 rising from and ex-

tending at an angle to the arms 38. The four arms of the members 31 and 32 have outwardly extending rest flanges 40 to be engaged by and support the arms 38 when in lowermost position.

It will be realized that when the parts are in the position shown in Fig. 1 of the drawings, the cooking utensils will rest directly on the arms and parts 31 and 32 against displacement; since in lateral movement it 75 would abut the arms 39. A pan may be disposed on top of the arms 39 if desired, to facilitate the radiation and dispersion of heat in the event it is desired that the stove should serve primarily as a heater. To facilitate packing or the occupation of small space, the members 38-39 may be moved upwardly from their pivots 37 to the dotted line position shown in Fig. 1.

I have found that in removing the stove 85 from a gas jet without closing the valve of the latter, sufficient gas will remain in the gas tube 8 and it will continue to burn to leave a flame at the tip of the gas jet.

Since merely the preferred embodiment of 90 the invention has been illustrated and described, it is to be understood that changes in the details of construction may be resorted to without departing from the spirit and scope as defined by appended claims. 95

I claim:

1. A stove having a burner and a gas tube leading thereto, an attaching member disposed axially of the tube and having a laterally extending lug, said tube having an 100 outwardly extending flange at its lower edge, a frame having an opening through which said tube extends, said frame resting on said lug, said frame having a leg overlapping said flange of the tube, a plate mounting said 105 attaching member and having a flange overlapping said flange of the tube, a second plate, said second plate being journaled on said attaching member and having a flange overlapping said flanges, and said plates 110 having coöperating openings whereby they serve as adjustable air inlet valve means.

2. A stove having a burner and a gas tube leading thereto, an attaching member, a frame surrounding said attaching member, a 115 flange on said tube, a leg on said attaching member and provided with a portion overlapping said flange, and fastening means for said flange and said leg.

3. A stove having a burner and a gas tube 120 leading thereto, an attaching member having a laterally extending lug, said tube having a flange at its lower edge, a frame having an opening to accommodate said tube, said frame having a leg overlapping said flange 125 of the tube, a mounting member for said attaching member and having a flange overlapping said flange of the tube, a plate journaled on said attaching member and having a flange overlapping said flanges, said plate 130

and said mounting member having coöperating openings whereby they serve as adjustable air inlet valve means.

4. In combination with a burner, a utensil supporting means, a supporting member rising from the burner and having a rest flange integral therewith, and a supporting member connected with said first mentioned supporting member and adapted to abut said

rest flange to limit movement in one direction.

In testimony whereof I affix my signature in presence of two witnesses.

ROBERT THOMPSON.
